UNITED STATES PATENT OFFICE.

JAMES M. ALLEN, OF ST. LOUIS, MISSOURI, ASSIGNOR TO FELLHAUER ALLEN MANUFACTURING COMPANY, OF ST. LOUIS, MISSOURI, A CORPORATION OF MISSOURI.

DESIGN FOR A SAFE.

43,260.

Specification for Design.

Patented Nov. 19, 1912.

Application filed July 8, 1912. Serial No. 708,365. Term of patent 14 years.

To all whom it may concern:

Be it known that I, JAMES M. ALLEN, a citizen of the United States, residing in St. Louis and State of Missouri, have invented a new, original, and ornamental Design for Safes, of which the following is a specification, reference being had to the accompanying drawing, forming a part thereof.

The figure in the drawing is a front elevational view of a safe showing my new design.

I claim:

The ornamental design for a safe as shown.

In testimony whereof I hereunto affix my signature in the presence of two witnesses, this 29th day of June, 1912.

JAMES M. ALLEN.

Witnesses:

MARTIN FELLHAUER,
A. B. LEWIS.
